CLAIM

The ornamental design for arcade game machine, as shown and described.

DESCRIPTION

FIG. 1 is a front perspective view of the arcade game machine.

FIG. 2 is a front view of the arcade game machine.

FIG. 3 is a rear view of the arcade game machine.

FIG. 4 is a plan view of the arcade game machine.

FIG. 5 is a right side view of the arcade game machine; and, FIG. 6 is a left side view of the arcade game machine.

FIGS. 1 to 6 illustrate a game machine with a “drive” type control panel without a bench.
